DESIGN FOR A FISH LURE

Wayne H. Carr, Kalamazoo, Mich.

Application May 7, 1947, Serial No. 138,866

Term of patent 3½ years

(Cl. D31—4)

To all whom it may concern:

Be it known that I, Wayne H. Carr, a citizen of the United States, residing at Kalamazoo, in the county of Kalamazoo and State of Michigan, have invented a new, original, and ornamental Design for a Fish Lure, of which the following is a specification, reference being had to the accompanying drawing, forming part thereof, in which:

Fig. 1 is a plan view, and

Fig. 2 is an edge or side view of a fish lure, showing my new design.

I claim:

The ornamental design for a fish lure, as shown.

WAYNE H. CARR.
